APPARATUS FOR MIXING AND CONDITION-
ING MASSECUITEEugene Roberts, Hastings, N. Y., assignor to The
Western States Machine Company, New York,
N. Y., a corporation of Utah

Application May 1, 1937, Serial No. 140,093

8 Claims. (Cl. 259—41)

This invention relates to apparatus for mixing and conditioning materials consisting of finely divided grains suspended in liquid, and it has particular reference to the provision of improved mixing apparatus for the conditioning of sugar massecuites preparatory to delivering charges of massecuite into centrifugal machines where sugar crystals and mother liquor forming the massecuite are separated by centrifugal force.

5 This application is in part a continuation of my co-pending application, Serial No. 10,317, filed March 9, 1935, for Apparatus for mixing massecuite.

In the production of sugar from relatively high grade syrups a relatively large quantity of syrup is boiled in a vacuum pan to cause the growth of sugar crystals, and after a massecuite of suitable consistency has been produced in the vacuum pan the entire body of massecuite, known as the "strike", is dropped from the vacuum pan into a large receiving tank positioned adjacent a battery of centrifugal machines. The centrifugals are of the well known gyratory suspension type embodying a perforated cylindrical basket provided with filter lining elements such that when a charge of massecuite from the receiving tank is introduced into a centrifugal and the centrifugal is revolved at a high speed the liquid content of the massecuite is expelled through the basket wall and the solid content, or sugar grain, is retained inside the basket by the filter lining elements. The receiving tank which receives the strike of massecuite from the vacuum pan communicates through a plurality of spaced ports with valve-controlled goose necks, each of which extends to a position overlying a centrifugal and is adapted to convey a charge of the massecuite into the corresponding centrifugal.

It has been the usual practice prior to my invention to mount in the bottom portion of the receiving tank, which is relatively narrow and trough-like in shape, a rotatable stirrer comprising an actuating shaft having projecting propeller blades. The revolution of the stirrer agitates the massecuite in the narrow bottom portion of the tank adjacent the outlet ports. I have found that this usual type of apparatus is not suited for optimum conditioning of the massecuite for centrifuging operations for several reasons. When a strike of massecuite is introduced into the tank the upper portion of the body of massecuite is permitted to lie relatively dormant, and agitation of the massecuite takes place to any substantial extent only in the region adjacent the outlet ports. Sugar massecuite

5 cuites have a natural tendency to settle, and with the usual type of mixing apparatus sugar grain from the upper portion of the tank settles to the lower portion and renders the charges of massecuite first withdrawn from the tank of considerably higher crystal content and less fluidity than charges last withdrawn. The last charges taken from the tank are of a sloppy consistency and are not suited for the same type of treatment as the first charges.

10 Another objectionable feature of the usual apparatus is that some of the massecuite in the receiving tank loses heat by conduction and radiation during processing of the strike. The loss of heat is not distributed uniformly throughout the batch of material, so that there are portions of the massecuite which cool relatively quickly as compared with other portions. For economical plant operations, it is desirable to boil massecuites to a high density and crystallization 15 before dropping them into receiving tanks. When in such condition, however, a very slight change in temperature has a pronounced effect on the fluidity of the massecuite. The cooling which occurs in the use of the apparatus of the prior art therefore causes the fluidity of charges 20 of massecuite withdrawn from the receiving tank at different times to vary even though the distribution of sugar grain throughout the batch be uniform. It also causes massecuite to cake and 25 cling to exposed parts inside the tank, so that burdensome and wasteful washing down of this caked material is necessary after each strike has been processed. At the centrifugal station the non-uniformity resulting from use of the 30 known apparatus makes it very difficult to adapt 35 centrifuging operations for the best treatment of each charge, and the sugar obtained from different charges but from the same strike of massecuite varies considerably in quality.

40 The prevailing practice is also to a large extent responsible for poor yields and low capacity at the centrifugal station. Yields are adversely affected by the necessity of adapting washing operations at the centrifugal station so that 45 charges which are most difficult to purge will be properly treated, as well as by the limitations imposed upon the degree of crystallization in the vacuum pan and by the loss of sugar due to caking in the tank. Lowered capacity is occasioned 50 by the difficulty of introducing the more viscous charges of massecuite into the centrifugals and by the inability to obtain best results on charges of non-uniform characteristics when employing 55

uniform short cycles of operation for the centrifugals.

It is an object of my invention to provide improved apparatus for mixing and conditioning 5 masscuites or like materials which keeps the consistency of a large batch of masscuite the same throughout the batch and thereby keeps uniform the sugar content of charges introduced 10 into a series of centrifugals and avoids caking, handling and centrifuging difficulties resulting from local cooling of the masscuite.

Another object of the invention is to provide improved mixing apparatus which not only keeps the consistency of the entire batch in the mixer 15 uniform but also supplies heat to the masscuite to compensate for heat losses through radiation and conduction and thereby keeps uniform the temperature and viscosity of all charges withdrawn from the batch from the beginning to the 20 end of the processing of a strike.

Another object of the invention is to provide mixing apparatus which includes a plurality of stirring means for maintaining the entire batch 25 of material in the apparatus in a thoroughly mixed condition, one of such stirring means constituting heat exchange means which enables efficient addition of heat to the masscuite without dilution thereof and which is so related to other stirring means that the heat thus supplied 30 is uniformly distributed throughout the batch.

I have found that it is possible to maintain uniform consistency of the masscuite throughout the entire batch in a receiving tank or mixer and largely to overcome difficulties heretofore incident to the mixing, charging and centrifuging operations by providing a mixing tank having a 35 relatively large upper portion in which is located large stirring means of a size and shape appropriate to the upper portion of the tank and a smaller lower tank portion in which is located 40 stirring means extending throughout substantially the entire length of the tank and adjacent outlet ports in the bottom thereof. I have found also that the stirring means in the lower 45 portion of the tank may be constructed as a stirring and heat exchange means and that apparatus so constructed will maintain the consistency of the masscuite uniform throughout the entire batch in the tank and also compensate for 50 heat losses occurring during the processing of the strike, so that every charge of masscuite introduced into the centrifugals, no matter whether at the beginning, in the middle or toward the end of the processing operations, is of the same consistency and fluidity as every other charge.

The accompanying drawings show preferred forms of apparatus which are illustrative of the many forms in which the principals of the invention may be embodied. In the drawings,

60 Figure 1 is a front elevation of one form of mixing and conditioning apparatus, the front wall being partly broken away to illustrate details of the interior construction.

Figure 2 is an end elevation of the same apparatus, showing driving means for actuating the stirring means of the apparatus and indicating the relation of the mixing apparatus to a centrifugal machine.

65 Figure 3 is a vertical cross section through the mixing tank of Figure 1, further illustrating the construction of stirring means therein.

70 Figure 4 is a front elevation of another embodiment of the invention, showing a mixing and conditioning tank in relation to a battery of cen-

trifugal machines and illustrating another form of stirring means.

Figure 5 is a vertical cross section through the mixing apparatus of Figure 4.

In Figures 1 to 3 of the drawings, the invention is illustrated as embodied in a usual and well known type of mixing tank including an elongated body portion 10, having end walls 11 and 13 and front and rear side walls 12 and 14, respectively, which define a relatively large upper tank portion 16 and converge toward the bottom of the tank to form a relatively narrow trough-like lower tank portion 18. Along the bottom wall of the tank a series of ports 20 is provided, each of which communicates with a goose neck 22 controlled by a valve 24, of known construction, and overlies the usual top opening of a conventional centrifugal 26.

The apparatus includes stirring means in both the upper and lower tank portions, which means are arranged to maintain continuous agitation of masscuite in the respective tank portions and to maintain movement of masscuite between the upper and lower tank portions so that the consistency of the entire batch in the tank 10 is always 20 uniform. Along the bottom portion of the tank and adjacent the outlet ports 20 stirring means is provided which keeps the material ready for introduction into the centrifugals thoroughly mixed and thereby requires that each centrifugal 25 of a series of centrifugals shall receive a charge of the same nature as that received by the others at any given stage of the processing operation. This lower stirring means in the illustrated form includes a shaft 28 extending the entire length of 30 the tank and carrying a plurality of radially extending blades 30 which are effective when revolved to cause continuous circulation of the masscuite. These blades 30 are preferably obliquely arranged so that the masscuite is propelled longitudinally and radially with respect to the shaft 28 as the lower stirring means is rotated.

In the upper portion of the tank stirring means is also provided, including a longitudinally extending shaft 32, a series of radial arms 34 secured 45 to the shaft and a plurality of longitudinal bars 36 secured to the arms 34. The principal work of stirring the masscuite in the tank 10 is performed by this larger stirring means in the upper tank portion. The two stirring means, however, are 50 arranged to move in paths which are spaced apart a suitable distance, and they together cause movement of masscuite back and forth between the upper and lower tank portions 16 and 18.

The stirring means may be rotated in any suitable manner, the illustrated driving mechanism including a pair of belt-driven pulleys 38 and 40, the former mounted loosely around an axle 42 and the latter keyed to a central gear 44. Gear 44 is in meshing relation with planetary stepped pinions 46 which are rotatably supported by portions of a cross head or frame 48 with the larger step of each pinion in mesh with the driving gear 44 and the smaller step in mesh with a surrounding fixed ring gear 50. The cross head 48 is secured to stub shaft 52 which in turn carries a spur gear 54 and is connected with the shaft 28 for the lower stirring means. Spur gear 54 meshes with a gear 56, and it in turn is in mesh with another spur gear 58 keyed to a part connected with shaft 52 for the upper stirring means. By an arrangement of this character relatively slow but powerful rotation may be imparted to both lower and upper stirring means.

In the preferred form of apparatus the main or 75

upper stirring means includes a plurality of stirring units, each including a pair of parallel radial arms 34. Longitudinally extending bars 36 constitute segments which bridge the arms of each unit and extend somewhat beyond the vertical planes in which lie their supporting arms. The ends of these bar segments are spaced somewhat from the ends of segments carried by an adjacent pair of arms 34, so that circulation of massecuite 5 takes place between stirring units as well as in and around the same. The ends of bars 36 adjacent the end walls of the mixing tank are arranged close to such walls, and the length and position of the radial arms 34 and the position of the outermost bars 36 on these arms are such that these parts move close to the side walls of the mixing tank during revolution of the stirrer. In addition, this arrangement is preferably so adapted to the dimensions of the tank that the outermost 10 bars are successively lifted out of and then dipped into the batch of massecuite in the tank during rotation of the stirring means.

The mixing and conditioning apparatus illustrated in Figures 1 to 3 maintains thorough mixing action on the entire mass of massecuite in the tank and prevents the settling of sugar grain toward the bottom portion 18. The distribution of granular and liquid material in the entire batch of massecuite is kept uniform at all times; hence 15 charging of the centrifugals is facilitated and the centrifuging operations may be adapted for the optimum results on material of continuing characteristics. The continuous agitation and mixing of the massecuite also overcomes problems heretofore occasioned by local cooling of the massecuite and thereby to a large extent does away with the adhesion of caked material on the walls of the mixing tank.

Another embodiment of my invention, which 20 is even preferable to the embodiment of Figures 1 to 3, is illustrated in Figures 4 and 5. The sole inadequacy of the apparatus of Figures 1 to 3 inclusive, is that it is incapable of entirely overcoming the effects of cooling of the massecuite during 25 the processing of a strike. The processing of a strike usually occupies a period in excess of an hour in actual refinery practice, and while the apparatus of Figures 1 to 3 will distribute the loss of temperature throughout the entire batch of 30 material it cannot avoid the decreased fluidity which necessarily results from even a small loss of temperature.

In the apparatus shown in Figure 4, I employ a mixing tank 100, somewhat like the tank 10 of 35 Figure 1, which embodies a relatively large upper tank portion 102 and a smaller trough-like portion 104. The bottom of the tank is ported and connected at the ports with a series of goosenecks 106, each leading to a centrifugal 108. In the upper portion of the tank I employ rotatable stirring means similar to the means described in connection with Figure 1, including a longitudinal shaft 110 to which are secured a plurality of radial arms 112 carrying longitudinal bars 114 for keeping the massecuite in a state of continuous and thorough agitation. In place of the lower stirring means of Figure 1, however, I provide in this embodiment a combined stirring and heat exchange means 116 which preferably is in the form 40 of a hollow longitudinally extending shaft 118 having connected thereto and communicating therewith a surrounding hollow coil 120.

This lower stirring and heat exchange means 45 116 is arranged with respect to other parts of the apparatus in substantially the same manner as

the lower stirring means of Figures 1 to 3, and its mechanical operation may also be similar. The principal difference between the two lies in the fact that means 116 provides conduits for the circulation of a heating liquid which may be introduced therewith from a pipe 122 and withdrawn through another pipe 124. As the stirring and heat exchange means is rotated a heated liquid is flowed through coil 120 from pipe 122 and hollow shaft 118, and the rate of flow and rate of movement of the coil are adapted so that dry heat will be supplied to the massecuite in amounts sufficient to counteract the loss of heat occurring in the entire body of massecuite from radiation and conduction. It will be apparent that the temperature of the liquid flowing through this system may be controlled in many ways. A suitable arrangement includes a heater 126 through which liquid from pipe 124 is circulated by a pump 128 and inside of which the liquid is heated to the desired temperature by steam introduced through a pipe 130. After the proper amount of heating has taken place the heated liquid passes out of the heater through a pipe 132 and thence into pipe 122. In a manner which will be readily understood by those skilled in the art, the amount of heat supplied to the liquid and thus to the massecuite in tank 100 is made responsive to the temperature of the massecuite itself through the use of a thermostatic device indicated generally at 134.

In operations of this preferred embodiment of the invention, I have found that dry heat may be supplied to the massecuite economically and efficiently through the revolving coil 120 and that the arrangement of this coil with respect to the upper stirring means in the tank 100 provides for uniform distribution of the heat throughout the entire body of massecuite in the tank. If a strike 40 of massecuite from a vacuum pan has been produced at a vacuum pan temperature of 185° F. the heat supplied to the massecuite after it has been introduced into the tank 100 is controlled so that the temperature in the tank is kept at substantially 45 185° from the time when the first charge is withdrawn for centrifuging until the strike has been completely exhausted. This heat may be supplied by circulating water or any other suitable liquid through the coil at temperatures not more than 30° in excess of the desired temperature of the massecuite, in accordance with the method described in United States Letters Patent 50 No. 2,055,778 granted to George E. Stevens on September 29, 1936. The coil is kept at a temperature sufficiently low to avoid local overheating or 55 caramelization of constituents of the massecuite, yet relative movement between the coil and massecuite serves to transfer the heat to the massecuite in the desired manner.

In the use of this apparatus all of the difficulties heretofore encountered in the handling of white massecuites and other high grade, free-purging massecuites between the vacuum pan and centrifuging stages are completely overcome, and important improvements in the quality of the sugar obtained from the centrifugals, the yield of sugar obtained from a strike of massecuite and the capacity of the centrifugal station are realized.

The degree of improvement is to some extent indicated by the following table showing results of actual sugar refinery operations, employing in "I" the type of mixing apparatus used prior to my invention and in "II" apparatus similar to that illustrated in Figures 3 and 4 of the drawings.

The massecuites were of comparable purity and density when dropped from the vacuum pans.

	I	II

15 Average pounds wash water required per 100 pounds of sugar.....	9.3	5.6

It will be understood by those familiar with the art that my invention is not restricted to embodiment in any particular form of stirring means, but that various constructions of stirring elements and various driving arrangements for them might be employed for performing the same operations and with substantially as desirable results as are obtained by the illustrated apparatus. Accordingly I desire that the invention be accorded a scope commensurate with the spirit of the specification with only such restrictions as are required by the claims.

I claim:

1. Apparatus for mixing sugar massecuites to maintain the consistency thereof uniform throughout substantially the entire batch, comprising an elongated mixing tank for holding a batch of massecuite having end walls and side walls which converge toward the bottom of the tank and define an enlarged upper tank portion and a communicating trough-like lower tank portion of sufficient capacity to accommodate several charges of massecuite for centrifugals, a plurality of spaced ports communicating with said trough-like tank portions for withdrawing charges of massecuite therefrom, rotatable stirring means extending substantially the entire length of the trough-like portion adjacent the bottom thereof and capable upon rotation of ensuring uniform consistency of the massecuite in individual charges withdrawn through said ports, and rotatable stirring means extending substantially the entire length of the tank in the upper portion thereof including stirring elements arranged to move in a path spaced vertically from the aforesaid stirring means and to maintain circulation of massecuite therebetween, and to move closely adjacent the end and side walls of said upper tank portion, whereby to keep substantially the entire batch of massecuite of uniform consistency and to inhibit caking against the tank walls.

2. Apparatus as claimed in claim 1 and means interconnecting said stirring means for simultaneous rotation.

3. Apparatus for mixing sugar massecuites to maintain the consistency thereof uniform throughout substantially the entire batch, comprising an elongated mixing tank for holding a batch of massecuite having end walls and side walls which converge toward the bottom of the tank and define an enlarged upper tank portion and a communicating trough-like lower tank portion of sufficient capacity to accommodate several charges of massecuite for centrifugals, a plurality of spaced ports communicating with said trough-like tank portion for withdrawing charges of massecuite therefrom, rotatable stirring means

extending substantially the entire length of the trough-like portion adjacent the bottom thereof and capable upon rotation of ensuring uniform consistency of the massecuite in individual charges withdrawn through said ports and rotatable stirring means extending substantially the entire length of the tank in the upper portion thereof including stirring elements arranged to move in a path spaced vertically from the aforesaid stirring means and to maintain circulation of massecuite therebetween, and to move closely adjacent the end and side walls of said upper tank portion, whereby to keep substantially the entire batch of massecuite of uniform consistency and to inhibit caking against the tank walls, said last-mentioned stirring means comprising a shaft extending longitudinally across the tank, a plurality of substantially parallel arms projecting radially from said shaft, and a plurality of bars carried by said arms in substantially parallel relation to said shaft.

4. Apparatus for mixing sugar massecuites to maintain the consistency thereof uniform throughout substantially the entire batch, comprising an elongated mixing tank for holding a batch of massecuite having end walls and side walls which converge toward the bottom of the tank and define an enlarged upper tank portion and a communicating trough-like lower tank portion of sufficient capacity to accommodate several charges of massecuite for centrifugals, a plurality of spaced ports communicating with said trough-like tank portion for withdrawing charges of massecuite therefrom, rotatable stirring means extending substantially the entire length of the trough-like portion adjacent the bottom thereof and capable upon rotation of ensuring uniform consistency of the massecuite in individual charges withdrawn through said ports, and rotatable stirring means extending substantially the entire length of the tank in the upper portion thereof including stirring elements arranged to move in a path spaced vertically from the aforesaid stirring means and to maintain circulation of massecuite therebetween, and to move closely adjacent the end and side walls of said upper tank portion, whereby to keep substantially the entire batch of massecuite of uniform consistency, and to inhibit caking against the tank walls, said last-mentioned stirring means comprising a shaft extending longitudinally across the tank and a plurality of stirring units projecting radially from said shaft so as to provide stirring facilities throughout the length of the tank, each of said stirring units including at least two substantially parallel radial arms and a plurality of bars carried by said arms in substantially parallel relation to said shaft, the adjacent ends of the bars of adjacent units being spaced apart to permit circulation of massecuite therebetween.

5. Apparatus for mixing sugar massecuites or the like comprising an elongated tank for holding a batch of massecuite having end walls and side walls which converge toward the bottom of the tank and define an upper tank portion of relatively large capacity and a communicating lower tank portion of sufficient capacity to accommodate several charges of massecuite for centrifugals, a plurality of spaced ports opening into said lower tank portion for withdrawing charges of massecuite therefrom, rotatable stirring means extending substantially the entire length of the lower tank portion and adjacent said ports and capable upon rotation of ensuring uniform consistency of the massecuite in indi-

- vidual charges withdrawn through the several ports, said stirring means having liquid circulation conduits in the interior thereof for accommodating a heating liquid, rotatable stirring means extending substantially the entire length of the tank in the upper portion thereof including stirring elements arranged to move in a path spaced vertically from the aforesaid stirring means and to maintain circulation of massecuite therebetween and to move closely adjacent the end and side walls of the upper tank portion whereby to keep uniform the consistency of massecuite to be fed from the upper tank portion to the lower tank portion and to inhibit caking of massecuite against the tank walls, and means for circulating a heating liquid through said conduits while the first recited stirring means is rotated whereby to supply heat to the massecuite and to maintain the temperature and fluidity of the entire batch substantially uniform throughout the processing thereof.
6. Apparatus for mixing a batch of sugar massecuite or the like during delivery of successive relatively small charges from the batch to a series of centrifugals comprising an elongated tank having a relatively large upper tank portion and a communicating trough-like lower tank portion provided with spaced discharge ports opening into its bottom and each communicating with a discharge chute overlying a centrifugal, main stirring means mounted in the upper tank portion and capable of keeping massecuite in said upper portion uniformly mixed comprising a rotatable shaft, a series of radiating arms secured thereto and longitudinally extending bars connecting adjacent pairs of said arms, rotatable stirring and heat exchange means extending substantially the entire length of the lower tank portion and adjacent said ports, and means for circulating a heated liquid through said stirring and heat exchange means, said main stirring means and last-recited stirring means arranged to move in vertically spaced paths but to maintain circulation of massecuite therebetween.
7. Apparatus for mixing a batch of sugar massecuite or the like during delivery of successive relatively small charges from the batch to a series of centrifugals comprising an elongated tank having a relatively large upper tank portion and a communicating trough-like lower tank portion provided with spaced discharge ports opening into its bottom and each communicating with a discharge chute overlying a centrifugal, main stirring means mounted in the upper tank portion and capable of keeping massecuite in said upper portion uniformly mixed comprising a rotatable shaft, a series of radiating arms secured thereto and longitudinally extending bars connecting adjacent pairs of said arms, rotatable stirring and heat exchange means including a hollow shaft and a surrounding hollow coil secured thereto and interiorly communicating therewith extending substantially the entire length of the lower tank portion and adjacent said ports, and means for circulating a heated liquid through said hollow shaft and coil, said main stirring means and last-recited stirring means arranged to move in vertically spaced paths but to maintain circulation of massecuite therebetween.

EUGENE ROBERTS.
